(57) CLAIM

The ornamental design for a body suit, as shown and described.

DESCRIPTION

FIG. 1 is a perspective view of a body suit of my claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

The dash-dot-dash broken lines in FIGS. 1-8 depict boundary lines which form no part of the claimed design. The broken line outline of the partial human figure in FIG. 8 assists in illustrating how the body suit may appear when in a position of use, but forms no part of the claimed design. The evenly spaced broken lines and unshaded surfaces along the interior of the body suit within FIGS. 1, 6, and 8 depict features of the body suit that form no part of the claimed design.
